UNITED STATES PATENT OFFICE.

FREDERIC T. DE LONG, OF CHICAGO, ILLINOIS, ASSIGNOR TO CHICAGO RAILWAY EQUIPMENT COMPANY, OF CHICAGO, ILLINOIS, A CORPORATION OF ILLINOIS.

SAFETY SUPPORT.

Application filed March 19, 1925. Serial No. 16,683.

This invention relates to new and useful improvements in safety supports for brake beams.

- The object of the present invention is to 5 provide a resilient support for normally supporting the brake beam and a rigid support adapted to engage and reinforce said resilient support when the latter is placed under unusual load.
- 10 Further objects of the invention are to provide a yielding support member for supporting a brake beam and a rigid support member disposed below and normally spaced from the first member so as not to 15 affect the normal operation thereof and adapted to reinforce the same and form a rigid support for the brake beam in case of the displacement of the latter.

With these and other objects in view, my 20 invention consists in certain novel features of construction and arrangement of parts, hereinafter more fully described and claimed, and illustrated in the accompanying drawings, in which—

25 Figure 1 is a side elevational view of my improved support.

Figure 2 is a transverse cross section taken on lines 2—2 of Figure 1.

30 Figure 3 is a transverse cross section of a modified form of support.

Figure 4 is a side elevational view of another modified form of support.

Figure 5 is a vertical cross section taken on line 5—5 of Figure 4.

35 In the present invention, the safety support is provided with a rigid member carried by a car truck part and disposed below that portion of the yielding member which is arranged below the compression member 40 of the brake beam. Thus the safety support is enabled to catch and safely support said brake beam in case the brake hanger breaks and releases the brake beam.

The invention embodies a resilient track 45 member underlying a brake beam and an auxiliary rigid member disposed below the former and normally spaced therefrom so as not to affect the resiliency thereof.

50 Referring by numerals to the accompanying drawings, 10 indicates a car truck part, such as a spring plank, 11 a compression member, and 12 a tension member of a brake beam. A bracket 14 having a curved portion 14^a is secured to the spring plank in any suitable manner, such as rivets 15, and

is provided with depending lugs or ears 16 which are apertured for receiving pins 17. Cotter pins 17^a are used to secure the pins 17 against removal.

In the form shown in Figures 1 and 2, a 60 yielding supporting member 18 provided in its central portion with a bend 18^a is adapted to be nested against the underside of said bracket with the bend 18^a engaging the curved portion 14^a of said bracket. The 65 ends of said yielding member extend under the brake beams and terminate in upwardly inclined portions 19 over which operate chairs 12^a carried by tension members 12. The member 18 is provided immediately adjacent to the ends of bracket 14 with upwardly and outwardly curved portions 20 which increase the flexibility of the outer ends of member 18 and also serve to space the same from the projecting ends 21 of a 70 rigid member 22 which forms the auxiliary brake beam support. Member 22 is provided with a centrally disposed bend 22^a which cooperates with the curved portion 18^a of member 18.

Normally the ends 21 of rigid member 22 are spaced from the yielding ends of member 18 and have no operative engagement therewith. However, when the brake beam falls either through the breakage of the 85 brake hanger or through some other cause, the weight of the brake beam depresses the ends of member 18 so that they come to rest on portions 21 of member 22 which forms a rigid support therefor and prevents further displacement of said resilient end and the brake beam.

In the form shown in Figures 1 and 2 the rigid member 22 is angle-shaped in cross section and the vertically disposed flange 90 thereof is provided with apertures for receiving pins 17. The upper faces of ends 21 are curved upwardly and outwardly to conform to the curvatures 20.

In the form shown in Figure 3, the rigid 100 member 24 is formed channel-shape and both of the vertically disposed flanges are apertured for receiving pins 17.

In the modified form shown in Figures 105 4 and 5, a bracket 25 is detachably secured to the spring plank by bolt and nut fastening devices 26 and is provided in its upper face with a longitudinally disposed channel for receiving the resilient member 18. The ends of bracket 25 terminate in exten- 110

sions 27 which extend a suitable distance past the spring plank under the resilient member and have their upper faces curved to correspond to the curved portions 20 of resilient member 18. Thus, instead of providing a separate member to form the rigid support, said support is formed integral with the bracket. The spacing of the ends of the rigid portions from the resilient member 18 permits free yielding movement of said resilient member within a predetermined range and said rigid members act as safety elements which reinforce the yielding member and which prevent the dropping of the brake beam to the ground in case the latter is displaced.

Obviously other changes in the construction and arrangement of parts of my improved brake beam support can be made and substituted for those herein shown and described without departing from the scope of my invention.

I claim:

1. A safety support for brake beams comprising a resilient track member, and a flanged member for supporting the said track member, said flanged member being provided with terminal portions normally spaced from said resilient track member and adapted to support and reinforce the same when the latter is flexed downwardly.

2. A safety support for brake beams comprising a yielding member for yieldingly supporting a brake beam, and a flanged member in fixed supporting relation with the central portion of said yielding member and provided with terminal portions underlying said yielding member and normally spaced therefrom and adapted to support and reinforce said yielding member when the latter is forced downwardly beyond a certain distance.

3. A safety support for brake beams comprising a yielding member adapted to yieldingly support a brake beam, and a bracket for supporting the central portion of said yielding member and having terminal portions normally spaced from said yielding member and engageable thereby when said member is flexed downwardly a predetermined distance.

4. In a car construction, the combination of a car truck part, a bracket carried there-

by, a resilient support member carried by said bracket and forming a yielding support 55 for a brake beam, said bracket being provided with terminal extensions normally spaced from said yielding member and adapted to be engaged thereby and support said brake beam when said yielding member 60 is subjected to excessive weight.

5. A safety support for brake beams comprising a plurality of members, one of said members being resilient and forming an operative yielding support for a brake beam 65 and the other of said members terminating short of said yielding member and held in fixed relation therewith and provided with downwardly flanged terminal extensions 70 normally spaced from said yielding member and adapted to reinforce said yielding member and form a rigid support for said brake beam.

6. A safety support for brake beams comprising an attaching bracket provided with 75 integral terminal extensions and a resilient supporting member mounted in said bracket and extending under the tension member of said brake beam to form a yielding track therefor, the terminal extensions of said 80 bracket being rigid and extending under said resilient member so as to reinforce the latter and form a rigid support for the compression member when the latter is displaced.

7. In a car construction, the combination with a part of a car truck, of a resilient member carried by said part for yieldingly supporting a brake beam, and a flanged support member supporting said yielding member and having a terminal extension underlying a portion of said resilient member and adapted to form a rigid support for said 90 brake beam.

8. A safety support for brake beams comprising a yielding support member for forming a third or fourth point support for brake beams, and a bracket for carrying said support member and having an extension underlying a portion of said yielding member and 100 normally spaced therefrom, said extension being adapted to catch and support said brake beam in case the latter is displaced.

In testimony whereof I hereunto affix my signature this 12th day of March, 1925.

FREDERIC T. DE LONG.
